ELECTROCHEMICAL STORAGE AND RETRIEVAL
UNIT FOR CARDS OR THE LIKE

Paul W. Porter, Marietta, Ohio, assignor to Sperry Rand
Corporation, New York, N.Y.

Filed Oct. 16, 1972, Ser. No. 300,396

Term of patent 14 years

Int. Cl. D6—04

U.S. Cl. D6—174

FIG. 1.

FIG. 2.

FIG. 3.

FIG. 4.

FIG. 1 is a front perspective view of an electromechanical storage and retrieval unit for cards or the like showing my new design;

FIG. 2 is a top plan view;

FIG. 3 is a front elevational view; and

FIG. 4 is a right side elevational view.

The back of the unit is plain and unornamented.

I claim:

The ornamental design for an electromechanical storage and retrieval unit for cards or the like, substantially as shown and described.
